UNITED STATES PATENT OFFICE

JOSEPH LEHMANN, OF PARIS, FRANCE.

APPARATUS FOR THE PREPARATION OF COLORLESS GLUE.

964,980.

Specification of Letters Patent. Patented July 19, 1910.

Application filed February 1, 1909. Serial No. 475,388.

To all whom it may concern:

Be it known that I, JOSEPH LEHMANN, residing at Paris, France, have invented certain new and useful Improvements in the Preparation of Colorless Glue, of which the following is a specification.

This invention relates to improvements in apparatus for the preparation of colorless glue, in which the material to be treated is fed to the interior of a rotatable drum composed of perforated material, said drum running in a casing containing hot water whereby the gelatin is separated from the insoluble matter, and in which a screw is provided in said drum for conveying the insoluble matter to the delivery end of the drum, the object being to obtain a colorless glue from the clippings and waste of hides and other glue making materials.

Under my invention I provide at the delivery end of the rotatable drum two or more curved blades mounted on the shaft of the screw, said curved blades taking up the insoluble matter and delivering it to a conical outlet pipe. The gelatinous solution is drawn off and clarified and is then passed over a rotary drying cylinder from which the thin layer of gelatin is removed and disintegrated, and the disintegrated or powdered gelatin is subjected to a current of air to hasten the cooling of the product.

In order that my invention may be clearly understood, I have hereunto appended explanatory drawings, whereon:

Figure 1 is a longitudinal section and Fig. 2 a sectional elevation of the apparatus on the lines X X Fig. 1.

The apparatus is composed of a casing or cylinder T in which is water A¹ heated by steam from a pipe v. In the interior of this casing and longitudinally thereof a cylindrical or polyhedral rotary receiver or drum V is arranged in which is fixed an Archimedean screw S connected with the drum V so as to rotate therewith, the screw shaft passing through the drum and casing. The drum is constructed of wire cloth or gauze upon an iron framing, the wire cloth or gauze being sufficiently fine to retain the insoluble matters in the interior of the compartments A and B of the drum V, but allowing the gelatinous solution to pass through, and the level of the water in the casing T being such that the lower part of the rotatable drum V runs in the water as shown at Fig. 1. At the front or loading

end of this receiver or drum V there is a hopper C into which the raw materials are put, and from which they run down by their own weight into the hot water. As the drum rotates the screw, which rotates with it carries the insoluble matters from the one end of the drum to the other, while the gelatin is dissolved in the liquid A¹ and is left in a state of solution. At the other extremity B of the cylinder, the insoluble matters are raised by the curved blades or elevators o, o¹, mounted on the screw shaft, see Fig. 2, and are discharged by the conical outlet pipe D (Fig. 1.) arranged on the casing around the screw shaft.

Before the glue making materials are introduced into the apparatus they are completed subdivided, washed and reduced to pulp by means of a crushing cylinder, similar to those at present used in paper making. When thus disintegrated and reduced to the condition of soup the insoluble materials lose their consistency and on being subjected to the action of boiling water they immediately give up the gelatin which is rendered free—hence its colorless character.

After extraction, the gelatinous solution may be clarified by means of the filter F and drawn out by the rotary pump P in order to be freed from grease in the reservoir R.

While the solution is still hot, no matter to what degree it may have been concentrated, it may be desiccated immediately. To effect this it is run by means of the cock r¹ into the hopper m. An opening or interval of about one quarter of a millimeter for example is left between the surface of the rotary drying cylinder J, which is heated by steam and the lower extremity of the hopper side or wall m. This interval allows the liquid to spread over the smooth surface of the rotary drying cylinder in a thin, uniform, and continuous layer. Exposed in that way, the liquid forms a thin sheet or skin of solid matter, and is dried completely. At that point the blade c which is arranged along the cylinder, detaches the skin or sheet while it is still hot and rather sticky, and the sheet is caused to fall between the longitudinal wings t of wire cloth which are fixed to the rotary disintegrating cylinder L. The sheet is disintegrated at the same time and the material is scattered in different directions as the result of the rotary movement of the disintegrating cylinder.

As the product cools it dries spontaneously and falls down at *n*.

The cooling is rapid owing to the slight thickness of the material, and it is still further hastened by the natural draft of air arranged between the cage *i* and the funnel or chimney *j*, the current of air traversing the wings of openwork and thus cooling the gelatin powder during motion.

10 The two cylinders *J*, *L*, turn at the same speed, say from 4 to 6 revolutions per minute. This speed may be varied by means of friction gear *l* as required, and according to the degree of concentration of the gelatin solution to be dried.

15 The extracting apparatus, and the mechanical drier as shown in Figs. 1 and 2, work very well at boiling temperature, say 100° C., but the temperature should not be allowed to exceed 106° centigrade.

20 Having now fully described my invention what I claim and desire to secure by Letters Patent is:—

1. The combination, in a glue manufacturing apparatus, of a casing for the reception of liquid, means for heating the liquid, a rotatable drum composed of perforated material located in said casing, means for feeding the material to be operated on into 25 said drum, a screw in said drum consisting of a shaft and rotary curved blades mounted on the shaft for the purpose of discharging the insoluble materials after passing along the drum.

30 2. The combination, in a glue manufacturing apparatus, of a casing for the reception of liquid, means for heating the liquid, a rotatable drum composed of perforated material located in said casing, means for feeding the material to be operated on into 35 said drum, a screw in said drum consisting of a shaft and rotary curved blades mounted on the shaft for the purpose of discharging the insoluble materials after passing along the drum, and a conical outlet pipe in said casing.

40 3. The combination, in a glue manufacturing apparatus, of a casing for the reception of liquid, means for heating the liquid, a rotatable drum composed of perforated material located in said casing, means for feeding the material to be operated on into 45 said drum, a screw in said drum consisting of a shaft and rotary curved blades mounted on the shaft for the purpose of discharging the insoluble materials after passing along the drum, and a conical outlet pipe in said casing.

4. The combination, in a glue manufacturing apparatus, of a casing for the reception of liquid, means for heating the liquid, a rotatable drum composed of perforated material located in said casing, means for feeding the material to be operated on into 50 said drum, a screw in said drum consisting of a shaft and rotary curved blades mounted on the shaft for the purpose of discharging the insoluble materials after passing along the drum, a conical outlet pipe in said casing, clarifying means arranged in connection with said casing and means for disintegrating and cooling the clarified product. 55

4. The combination, in a glue manufacturing apparatus, of a casing for the reception of liquid, means for heating the liquid, a rotatable drum composed of perforated material located in said casing, means for feeding the material to be operated on into 60 said drum, a screw in said drum consisting of a shaft and rotary curved blades mounted on the shaft for the purpose of discharging the insoluble materials after passing along the drum, a conical outlet pipe in said casing, clarifying means arranged in connection with said casing and means for disintegrating the clarified product and means for cooling the clarified product comprising an 65 openwork cage to which the said product is delivered and a chimney in connection with said cage for causing an air current to traverse the cage. 70

5. The combination, in a glue manufacturing apparatus, of a casing for the reception of liquid, means for heating the liquid, a rotatable drum composed of perforated material located in said casing, means for feeding the material to be operated on into 75 said drum, a screw in said drum consisting of a shaft and rotary curved blades mounted on the shaft for the purpose of discharging the insoluble materials from the drum, a conical outlet pipe in said casing, means for 80 clarifying the extracted gelatinous solution comprising a filter, a rotary pump and a grease reservoir, means for desiccating the clarified solution comprising a hopper under said grease chamber and a rotary heated 85 drying cylinder mounted beneath said hopper, a blade in contact with the cylinder and a winged rotary disintegrating cylinder mounted beneath said blade, and means for hastening the cooling of the finished product. 90

In testimony whereof I affix my signature in presence of two witnesses.

JOSEPH LEHMANN.
